UNITED STATES PATENT OFFICE.

JACOB J. WOLFE, OF NORTH MANCHESTER, INDIANA, ASSIGNOR TO THE PEABODY SCHOOL FURNITURE COMPANY, OF NORTH MANCHESTER, INDIANA, A CORPORATION OF INDIANA.

FOLDING CHAIR.

1,284,526.

Specification of Letters Patent. Patented Nov. 12, 1918.

Application filed April 16, 1918. Serial No. 228,942.

To all whom it may concern:

Be it known that I, JACOB J. WOLFE, a citizen of the United States, residing at North Manchester, in the county of Wabash and State of Indiana, have invented certain new and useful Improvements in Folding Chairs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to folding chairs and has for its object to provide a chair of this class which is so constructed and arranged that it will not tip forward when the weight of the user is disposed on the front edge of the seat.

A further object of the invention is to provide a folding chair which will fold absolutely flat and within the two long leg members of the chair.

A further object of the invention is to provide a folding chair which is extremely rigid and free from wobble when in use.

A further object of the invention is to provide a folding chair so constructed and arranged that the weight of the occupant is delivered to the soundly braced long leg pieces in such manner that the chair will withstand many times more weight than it would ever receive in ordinary use.

A further object of the invention is to provide a folding chair, the hinging connections of which are so constructed and arranged that the seat when folded is substantially locked in folded position and will, therefore, not become accidentally unfolded during transportation or while quickly or roughly handling the same.

In folding chairs as usually constructed, they do not readily stack or pack in such manner that they entirely serve the purposes for which they are constructed, because of the fact that for the most part they do not fold flat and are also hampered by projections and extensions which prevent a perfectly flat stacking of the chairs. Furthermore chairs of this class as usually constructed are quite fragile and do not provide a rigid structure, while they are for the most part extremely liable to become accidentally

unfolded as when quickly or roughly handling the same, as it is, of course, understood that for assembly purposes, chairs of this character are handled in large numbers and must be quickly moved and positioned.

This invention consists in the novel construction of the chair and particularly in the novel construction and arrangement of the long leg members and in the hinging construction for the back and seat sections and the short leg members which provides for an absolutely flat folding of the chair and which further provides for a substantially locking of the chair in a folded position, to such extent that the chair will not readily become accidentally unfolded.

Referring to the accompanying drawings—

Figure 1 is a side elevation of the folding chair in unfolded position constructed in accordance with this invention.

Fig. 2 is a front elevation of the same.

Fig. 3 is a vertical sectional view through the chair in folded position taken on line 3—3 of Fig. 4.

Fig. 4 is a front elevation of the chair in partially folded position and

Fig. 5 is a vertical sectional view taken on the same line as Fig. 3, and illustrating the chair in partially folded position.

Fig. 6 is a fragmentary transverse sectional view through the seat and short leg member, taken on line 6—6 of Fig. 4.

Like numerals of reference indicate the same parts throughout the several figures, in which—

1 indicates the chair comprising the two long leg members 2 and the two short leg members 3, the seat 4 and the back 5.

As will appear from Fig. 4, the two long leg members 2 are tied together at their tops by a mortised-in-back-rail 6 and are also rodded together just under the rail 6 and toward the rear edges of the pieces 2 by a metal rod 7. The said two long leg pieces are also tied together near their centers by a gained-in strip 8 set in the front edges of the two pieces 2, so that the face of the strip 8 is flush with the front edges of the leg pieces 2. The said two long leg pieces 2 are also tied together near their bottoms by a round or stretcher 9.

Referring now to the short leg pieces 3, it will be seen that the same are hinged or

members, the said pivotal connection between the said links and the said seat and the said pivotal connection between the said seat and the short leg members passing the 5 pivotal point between the said links and the long leg members when the seat is being folded so as to lie beyond and in rear of the pivotal point of the links and the long leg members when the said seat is in a folded 10 position.

3. A folding chair, including a pair of long leg members, a pair of short leg members pivoted on said long leg members at a point in rear of the longitudinal center line 15 of the long leg members, a back having movable connection with the long leg members at a point therein in rear of the longitudinal center line thereof, said back having movable connection with the said short leg members at a point in rear of the longitudinal 20

center line of said short leg members, a seat, a pair of links having pivotal connection with said seat and pivotal connection with said long leg members at a point in front of the longitudinal center line thereof, the 25 whole arranged in such manner that the short leg members and the seat and back will fold within the said long leg members on either side of the longitudinal center thereof whereby the said short leg members, the seat 30 and back lie entirely within the said long leg members when the chair is in a full folded position.

In testimony whereof, I affix my signature, in presence of two witnesses.

JACOB J. WOLFE.
